UNITED STATES PATENT OFFICE.

JAMES MONROE BRADSHAW AND WILLIAM EDGAR MEEK, OF EASTONVILLE,
COLORADO.

BAG-HOLDER.

SPECIFICATION forming part of Letters Patent No. 399,373, dated March 12, 1889.

Application filed August 16, 1888. Serial No. 282,895. (No model.)

To all whom it may concern:

Be it known that we, JAMES MONROE BRADSHAW and WILLIAM EDGAR MEEK, citizens of the United States, residing at Eastonville, 5 in the county of El Paso and State of Colorado, have invented new and useful Improvements in Sack-Holders, of which the following is a specification.

Our invention relates to improvements in 10 sack-holders; and it consists in certain novel features hereinafter described and claimed.

In the accompanying drawings, which fully illustrate our invention, Figure 1 is a perspective view of a separator provided with our 15 improved bag-holding device. Fig. 2 is a detail perspective view of the bag-holder, looking at the opposite side to that seen in Fig. 1. Fig. 3 is an elevation showing a slightly-modified arrangement, and Fig. 4 is a similar view 20 showing a simplified form of the device.

Referring to the drawings by letter, A designates a separator having the frame-work B, provided with the usual runners, D, and uprights C.

25 E designates the shaking-shoe suspended within the frame-work B, and having an upper screen discharging at the end of the frame-work and an under screen discharging at a point within the frame-work. We provide a bag-holder at the end of the frame-work to receive the commodities discharged from the upper screen, and also another within the frame-work to receive the commodities discharged from the under screen.

35 F designates a swinging base or platform, which is pivoted at or near one end to one of the transverse bars of the main frame, as at f, and on this base or platform are secured standards G, connected at their lower ends by 40 a bow, g, which is bolted to the platform. The upper ends of these standards are slotted longitudinally, as at g', and on these standards is adjustably secured a plate, H, by means of bolts and nuts to adapt the device 45 to supports bags of different lengths, the bolts passing through the plate and the slots in the standards, and the nuts bearing against the standards or plate, as is obvious.

I designates a lever that is pivoted at one 50 end to the plate H and has its opposite end

extended beyond the plate and provided with a handle for its convenient operation. This lever is provided with two upwardly-extended arms, i, that are arranged to move through a guide, i', at the upper end of the plate H, and the upper ends of these arms are projected above the upper edge of the plate H, and are pointed to enter the bag that is to be suspended therefrom. The free end of the pivoted lever I is arranged to move within a 60 guide, i', secured on the plate H, near one edge thereof, and the lever is normally pressed upward, so that the pointed ends of its arms are projected above the plate H by means of a spring, J, that is connected at one end to 65 the lever and at its other end to the plate H.

K designates a yielding standard, preferably formed of spring metal, secured at its lower end to the base at a short distance from the lever, and this standard has an angular 70 head, k. This angular head is made separate from the standard, which is slotted at its upper end. A bolt, k', passes through the slot in the standard and an opening in the angular head, and the threaded end of the bolt receives a nut, whereby the head can be readily detached and adjusted vertically to the same plane as the plate H, for supporting bags of different lengths in a vertical position.

L designates a funnel-shaped conducting 80 plate or spout that is hinged at one edge to the upper end of the plate H, and is adapted to fold upwardly to permit a bag to be suspended or removed from the arms i and standard K, said plate or spout being arranged 85 over the mouth of the bag to conduct the contents of the under screen of the shoe into said bag.

To secure a bag to the arms i and standard k, the pivoted base or platform is swung outward, so that the inner end thereof is outside of the frame, after which the hinged or pivoted spout or plate L is turned to a vertical position and the bag connected to the arms i and the angular head of the yielding standard. The 90 pivoted base is then swung beneath the shoe, so that the spout L is beneath the discharge-opening in the lower screen to properly conduct the commodity discharged therefrom into 95 the bag.

To detach the bag from the spring-standard and the arms of the pivoted lever, the latter is depressed to draw the points of said arms away from and out of contact with the edges of the 5 mouth of the bag and against the tension of the spring of the lever J, which, upon being released, automatically returns to its normal position.

When the prongs of the arms are released 10 from a bag, the yielding standard springs outwardly and supports the bag in an upright position until the bag is removed from said standard for the purpose of tying up its mouth.

15 In Fig. 3 we have shown a somewhat modified arrangement especially adapted for use at the end of the separator. In this arrangement the uprights C are provided with vertical longitudinal slots, and a frame, M, is adjustably secured between the same by means of bolts inserted through said frame and the slots in the uprights and nuts mounted on said bolts and adapted to bear against the uprights, as will be readily understood. This 20 frame M comprises a horizontal cross-bar, m, and the vertical depending arms $m'm^2$ at the ends of same, and the securing-bolts are inserted through said arms. An inclined discharge-board, N, is bolted to the cross-bar, as 25 shown, in position to direct the commodity discharged from the upper screen into the bag. One end of a lever, O, is pivoted to a lug, P, formed on the vertical arm m' , while the free end of the lever plays within a keeper, 30 p , and is held normally elevated by a spring, p' , having one end secured to the arm m^2 and its other end bearing against the under edge of the lever. This lever carries the vertical pointed arms R, which project upward through 35 suitable openings in the discharge-board in position to engage the edge of the bag.

Q is a yielding standard provided with an angular head, q, and similar in all respects to the standard K, and secured to a platform, q' , 40 secured upon the extended ends of the runners, as shown.

In Fig. 4 we have shown a slight modification of our device. In this form of our device the adjustable frame is dispensed with 45 and the discharge-board is secured to and between the uprights. The lever and the guide

therefor are also secured to the uprights, and instead of the spring shown in the other figures we provide a standard, S, having a reduced bifurcated upper end in which the lever plays, and a spring, T, is coiled around this reduced end and bears against the lever and the shoulder of the standard. 55

Having thus described our invention, we claim—

1. A bag-holder comprising a yielding standard having a longitudinal slot at its upper end, an angular head, a bolt passed through the head and the slot in the standard to adjustably secure the head to the standard, and 60 a lever supported at a slight distance from the said standard and carrying bag-retaining prongs, as set forth.

2. A bag-holder comprising a support, a yielding standard arranged a slight distance 70 from said support, a lever mounted on said support, and bag-retaining prongs carried by said lever, as set forth.

3. A bag-holder comprising a yielding standard, a vertically-adjustable support arranged 75 a slight distance from the yielding standard, a lever mounted on said support, bag-retaining prongs carried by said lever, and a spring having one end secured to said support and its other end bearing against the under side 80 of the lever, as set forth.

4. The combination of the horizontally-swinging base, the standards erected thereon, the plate H, adjustably secured to said standards, the lever pivoted to said plate, and 85 the bag-retaining prongs carried by said lever, as set forth.

5. The combination of the standards G G, the plate H, secured to said standards and adjustable vertically thereon, the guides i^1 i^2 90 on said plate, the lever pivoted on the plate and projecting through the guide i^2 , and the bag-retaining prongs carried by the lever and extending through the guide i^1 , as set forth.

In testimony that we claim the foregoing as 95 our own we have hereto affixed our signatures in presence of two witnesses.

JAMES MONROE BRADSHAW.

WILLIAM EDGAR MEEK.
